Primary Examiner — Manpreet S Matharu*Assistant Examiner* — Suzanne E Tisdell(74) *Attorney, Agent, or Firm* — Saidman DesignLaw Group, LLC(57) **CLAIM**

The ornamental design for a vehicle, as shown and described.

DESCRIPTION

FIG. 1 is a perspective view of a vehicle showing my new design;

FIG. 2 is a front view thereof, the rear view being a mirror image;

FIG. 3 is a left side view thereof, the right side view being a mirror image;

FIG. 4 is a top view thereof; and,

FIG. 5 is a bottom view thereof.

The drawings include surface shading which illustrates contour and not surface ornamentation.

The oblique shade lines indicate transparency and not surface decoration.

1 Claim, 5 Drawing Sheets(56)
